US00D575490S

(12) United States Design Patent
Hatfield et al.

(10) Patent No.: US D575,490 S
(45) Date of Patent:  Aug. 26, 2008

(54) SHOE UPPER

(75) Inventors: Tinker L. Hatfield, Portland, OR (US);
Mark J. Smith, Portland, OR (US);
Thomas Foxen, Portland, OR (US);
Thomas Berend, Beaverton, OR (US);
Jeffrey Christopher Spanks, Portland, OR (US)

(73) Assignee: NIKE, Inc., Beaverton, OR (US)

() Term: 14 Years

(21) Appl. No.: 29/281,397

(22) Filed: Jun. 21, 2007

(51) LOC (8) Cl. 02-99

(52) U.S. Cl. D2/969

(58) Field of Classification Search D2/902,
D2/906-908, 943, 944, 969, 972-974, 945;
36/45, 77 M, 77 R, 83, 113, 114, 126-131
